9188

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,030, dated May 27, 1884.

Application filed March 27, 1884. Term of patent 3 $\frac{1}{2}$ years.

To all whom it may concern:

Be it known that I, LOUISE TULLY, of the city, county, and State of New York, have invented and produced a new and original Design for a Pattern of a Lady's Costume, (numbered 9,188;) and I do hereby declare that the engraved prints accompanying this specification convey to any one accustomed to using paper patterns a clear understanding of how a garment made up by the pattern will appear.

The design shows a round walking-skirt and an overdress; the skirt displays rounding panier draperies lapping broadly at the front ends, and exhibiting draping plaits in their upper and back edges; the overdress displays a closely-fitted basque-back that exhibits a deep, full back-drapery showing draping plaits in

its front edges and at the center, and a gathering near the top; closely-fitted, pointed basque-fronts; a narrow vest-section pointed at the top and bottom; surplice ornaments displaying shirrings in both ends; coat-sleeves exhibiting rolling cuffs flaring at their back edges, and a standing collar.

What I claim as my invention, and desire to secure by Letters Patent, is—

The design for a lady's costume, as shown in the engraved prints accompanying this specification.

LOUISE TULLY.

Witnesses:

ALFRED FRANCIS,
JOHN HENRY DRURY.
